assignors to Gaylord Products, Incorporated, Chicago,
Ill., a corporation of Delaware

Application March 22, 1954, Serial No. 29,621

Term of patent 14 years

(Cl. D14—30)

To all whom it may concern:

Be it known, that we, James K. Gaylord and Lewis E. Thatcher, citizens of the United States, residing at Chicago, county of Cook, and State of Illinois, have invented a new, original, and ornamental Design for a Wheel Cover, of which the following is a specification, reference being had to the accompanying drawing, forming part thereof.

Fig. 1 is a side elevational view of a wheel cover showing our new design.

Fig. 2 is an end view thereof with a portion in section as indicated by line 2—2 in Fig. 1.

We claim:

The ornamental design for a wheel cover, substantially as shown.
